UNITED STATES PATENT OFFICE.

ARCHELAUS PUGH, OF ST. PAUL, MINNESOTA.

HOISTING-MACHINE.

SPECIFICATION forming part of Letters Patent No. 320,886, dated June 23, 1885.

Application filed May 21, 1885. (No model.)

To all whom it may concern:

Be it known that I, ARCHELAUS PUGH, a citizen of the United States, and a resident of St. Paul, in the county of Ramsey and State 5 of Minnesota, have invented certain new and useful Improvements in Hoisting-Machines, of which the following is a specification.

This invention is intended to be used in elevating coal and similar material from the holds 10 of vessels, &c., and transferring it to small cars, and from thence to the dumping-grounds, platforms, or "pockets;" and it consists in the construction, combination, and arrangement 15 of parts, as hereinafter shown and described, and then sought to be specifically defined by the claims.

The invention may also be used under some 20 circumstances in other places than on docks, and for other purposes than in unloading vessels.

In the drawings, Figure 1 is a semi-sectional side elevation, and Fig. 2 is a rear elevation, 25 of one of the machines. Fig. 3 is a plan view in section on the line $x-x$ of Fig. 1. Fig. 4 is a plan view in section on the line $y-y$ of Fig. 1. Figs. 5 and 6 are enlarged details of the boom-supporting hangers. Fig. 7 is a plan view of the trestle-work and track system on which the dumping-cars travel. Fig. 8 is an 30 enlarged detail of the bucket and car operating drums. Figs. 9, 10, and 11 are enlarged views of one of the cars.

The machine consists, generally, in a large 35 frame-work mounted upon trucks adapted to travel upon a track or tracks upon a trestle-work or other suitable support along the edge of a dock at which the vessel to be unloaded is moored, and supporting an adjustable boom by which the hoisting-bucket is adapted to be 40 elevated, the frame-work also carrying in its lower part a "hopper" or receiver and the hoisting-cable operating-drums and other machinery. Generally such a construction and apparatus is not novel, my invention consisting 45 in the specific construction and arrangement of the boom and the hoisting apparatus or machinery, and also in a system of tracks and automatic dumping-cars by which the coal, &c., may be conveyed to any part of the 50 dock or other place of storage or into railroad-cars or other vehicles.

As before stated, this apparatus may be used in handling other material than coal, and in connection with other vehicles than vessels; but generally it will be used as shown and described. 5

A represents the frame or trestle-work erected 6 along the dock at which the vessel to be unloaded is moored, and will consist of piling and stringers constructed in the ordinary manner and having tracks $a-a-a$ along its top parallel with the water frontage.

The frame-work supporting the boom is formed, as shown, by open timber-work B', having truck-wheels b beneath it, resting upon the tracks $a-a-a$, by which means the frame-work B' may be moved along the dock frontage to any desired extent. The frame-work B' is tapered inward at its upper part, so as to render it less top-heavy, and is provided with an out-hanging frame, B², from which the outer end of the boom is suspended by guys, &c. 6

The boom consists of a horizontal section, C', suspended by hanger-rods B³ from a cross-timber, B⁴, on the front of the frame B', about half-way up from its bottom, and with its rear portion passing through and pivoted in an upright frame, C², adapted to swing around on centers d. The remainder of the boom consists of a swinging downwardly-inclined section, C², hinged to the outer end of the horizontal section C', and connected by the stay-rods or guys e to the upper part of the out-hanger B². By this means the inclined section C² of the boom may be hoisted up against the out-hanger, to be out of the way when not in use. When lowered down, this hinged section C² will project outward and downward over the vessel to be unloaded. In the drawings this adjustable section C² of the boom is shown broken out to denote that the inclined section is longer than is shown in the drawings. The inclined section of course may be of any length desired. 8

The hanger-rods B³, by which the forward end of the horizontal section C' of the boom is held, are merely bent rods with hooked lower ends, and adapted to enclose the cross-timber B⁴ and embrace the boom by their hooked ends. Thus the spaces between the booms and the upper sides of the booms are left entirely 9

unobstructed, so that a truck or carrier, D', may travel up the inclined section C', through the hangers B³, and along the horizontal section C' without obstruction.

The boom is formed of timbers set a few inches apart and held apart at their ends, leaving the space between them for their whole lengths entirely unobstructed, so that the hoisting-cable g, passing down between them, may run the entire length of the boom without obstruction.

The truck D', before mentioned, consists of a frame mounted on flanged wheels which run upon the upper surfaces of the two boom-sections C' C² as tracks, and is provided with a central grooved wheel or sheave, h', over which the hoisting-cable g runs. One end of this cable g is fastened to the lower side of the truck D', and runs downward around a sheave, E', upward over the sheave h', and thence over a third sheave, h², on a truck, D², mounted upon the horizontal section C' of the boom, and thence around a sheave, h³, at the rear end of the boom, and thence down to the hoisting machinery, to be hereinafter described.

The truck D² has a third bearing wheel or wheels adapted to travel along the under side of the horizontal section C' of the boom to prevent the truck from cramping upon the boom-section. The outer end of the truck is provided with a projection or stop, i', against which a corresponding projection, i², on the truck D' is adapted to strike when the latter runs up the inclined section C² of the boom, as hereinafter shown.

Attached to the sides of the horizontal section C' of the boom are small tracks or guides m', in which small wheels or rollers m² are adapted to run. Attached to each of these rollers, and hanging downward therefrom on each side of the boom, are triangular frames m³, connected across their lower ends by a cross-bar or stop, m⁴.

The truck D² has a rope or cable, n', attached to it and running forward over a sheave, n², on the side of the horizontal section C' of the boom, and thence back over a sheave, n³, and down to a weight, n⁴. By this means the truck D² will be held normally forward toward the upper end of the inclined section C² of the boom, as shown in Fig. 1.

There are many forms of hoisting-buckets used in connection with this class of machine; but I have shown in the drawings an approved form of bucket consisting, as shown, of the body G', having a bale, G², hinged to the body a short distance below its center, so that the bucket will dump itself, and adapted to be attached to the hook E' of the frame-supporting sheave E', and held upright and prevented from dumping by a tripping mechanism consisting of a lever, G³, hinged to the bale G² of the bucket and hooked over the edge of the bucket at p'. The upper part of this tripping-lever is provided with an extended or forked end, p², which is adapted to strike upon the cross-bar m⁴, connecting the lower ends of

the frame m³, when the bucket is elevated, as hereinafter shown.

Built into the frame-work B' is a hopper or receptacle, B⁵, having a sliding door, B⁶, by which its contents may be discharged into a small car, K', running upon tracks t on the floor B⁷ of the frame-work B'. The trestle-work A is extended backward from the frame B', and is provided with small tracks t' at right angles to the main tracks a' a² a³, these latter tracks being on a line level with the tracks t on which the cars K' run. They will be extended to any distance and any number 80 may be used, and they may be arranged with switches, if desired, to enable the small cars to be run in any desired direction. A portion of one of these systems of extension-tracks is shown in Fig. 7, in which is also exhibited 85 a portion of the main trestle-work A and the rail a², and a section of the frame B' and floor B⁷ of one of the movable hoisting-machines, to show that the rails t on which the car K' runs, when on the floor B⁷, may be set to join 90 the rails t' of the extended-track system, so that the cars may run from the rails t upon the rails t'. The ends of the rails t' next to the rails t will be jointed and movable from side to side, like switches on ordinary railroads, so 95 that the rails t' may be adjusted to correspond to the rails t where the location of the hatchways of the vessels will not permit the hoisting-machine to be set so as to bring the rails t' opposite each other.

Another advantage of the switches in the rail t' is that it enables me to adjust the rails t' to the rails t, which is much easier than it is to move the whole hoisting-machine to adapt the rails t to the rails t'.

Running along the system of extended tracks t', at right angles to them and parallel with the rails a' a² a³, is another pair of rails, t², with a turn-table, T, at each junction of the rails t' and t², so that the cars K' may be transferred 110 from one track t' to the other, to enable the coal, &c., to be carried to any part of the system.

The bucket G will usually be made to hold about one ton of coal, and each of the cars K' 115 will be made to hold two or more tons, while the hopper B⁵ may be formed large enough to hold any amount.

I claim a great advantage by this manner of arranging the boom, with one portion horizontal and the other portion inclined, as the bucket can thereby be dumped into the hopper B⁵ at its lowest possible point, so that the coal will not fall farther than is absolutely necessary to empty the bucket. With an elevating-boom running upward and backward at an angle and without the "joint" in it, it is necessary, in order to get the bucket over the hopper far enough to dump it, to elevate it for some distance up the inclined boom after it 130 passes over the edge of the hopper, thus causing the coal to fall a greater distance than is necessary to merely empty the bucket, where-as with my arrangement the distance between

the top of the hopper and the horizontal part C' of the boom need only be sufficient to permit the passage of the bucket G' and its bale G² and hoisting-sheave E' over the edge of the 5 hopper B⁵. The bucket then travels along the horizontal portion of the boom, and of course is not elevated any higher, so that when dumped the coal falls only a very little farther than the depth of the hopper, and will not be broken 10 or injured.

The coal is generally graded as to size at the mines or at the shipping-points, and it is desirable to keep it in the same condition to save the expense of regrading, &c.; hence the advantage 15 of an apparatus that will not break the larger pieces into smaller pieces, and thus change the grade.

When the truck D' runs from the inclined section C² of the boom upon the horizontal section C', its projection i' strikes the projections i' on the truck D², and from that point the truck D' carries the truck D² with it along the horizontal section C' of the boom, and at the same time draws the cable n' backward and elevates 25 the weight n', the fork p' on the trip-lever G³ at the same time striking the cross-bar m⁴ of the trip and dumping the bucket. Then the hoisting-cable g will be released, and the weight n' will draw the truck D² outward again and 30 push the truck D' outward over the point where the two parts C' C² are joined, and down upon the inclined section of the boom. From this point the weight of the bucket will be sufficient to draw the truck D' down the inclined 35 section of the boom and lower the bucket G' automatically again into the hold of the vessel, the function of the truck D² being merely to push the truck D' off from the horizontal section of the boom upon the inclined section 40 C² again to insure the return of the bucket to the vessel.

The projections or bumpers i' i² will be provided with springs to receive the impact of the flow when they come together and thus 45 prevent concussion from breaking any of the parts.

The trip-frame m³ m⁴ will be provided with a cable, m⁵, and weight m⁶, similar to the cable and weight n' n⁴, attached to the truck D², by 50 which it may be held forward in the position shown in Fig. 1.

The weight m⁶ will be sufficiently heavy to hold the trip m³ m⁴ with considerable force, so that under ordinary circumstances it will offer 55 resistance enough to cause the lever G³ to be thrown out of contact with the bucket G' when the trip-lever strikes the bar m⁴; but should the trip-lever become caught or cramped by any means the trip will be drawn along the 60 tracks m', and thus avoid the breakage of the trip-lever, bale, or other parts of the apparatus. The trip is thus a flexible safety attachment to the apparatus.

The hinging of the joint in the boom C' C² is 65 not an essential feature to the perfect operation of the apparatus, as far as the mere hoisting of the bucket and dumping it into the

hopper is concerned; but the hinge in the boom, as before stated, enables the part C² to be hoisted up out of the way when not in use, 70 which is a very important advantage, as the boom is not then in danger of being struck by the rigging of passing vessels, neither will the boom strike the rigging of vessels when the hoisting-machines are being moved along the 75 trestle-work A.

The "outhanger" is formed by two inclined timbers, B², bolted to the sides of the framework B', and extending up above the framework and connected across the top by a cross-tie or timber, B⁸. The guy-ropes e or hoisting-ropes of the adjustable boom-section C² are connected to the outer end of this cross-timber B⁸, and converge inward toward and are attached to the boom by straps or bales w. 80 The suspension-hangers B³ are adapted to be moved along the cross timber B⁴, as before described, so that the outer end of the boom may be swung around on the centers d to adapt it to the hatchways of the vessel to be 85 unloaded. By drawing upon one set of the guy-ropes or hoisting-cables e and loosening up the other set the boom may be drawn around from side to side, this movement being limited only by the width between the 90 timbers B', but will be sufficient for all ordinary purposes.

The lateral adjustment of the boom is a very important feature of my invention, as I am enabled thereby to adapt the boom to the 100 hatchways of the vessels without moving the frame-work B', which is frequently a very important advantage. This lateral adjustment also enables me to use two of the hoisting-machines in one hatchway, as the booms of the 105 two frame-works B' may be set toward each other without causing the frames to interfere.

Another advantage gained by the lateral adjustment of the boom is that the hoisting-frame may be moved along far enough to set its rails t opposite one of the pairs of rails t' other than the pair which naturally come opposite to it when the boom is at right angles to it, so that the coal may be delivered upon 110 any one of three or four of the sets of rails t' without moving the vessel.

I do not wish to be confined to the precise construction of the boom and its connections, as shown in the drawings, as I am aware that 115 modifications under certain circumstances might be advisable or necessary.

On the floor B⁷ of the frame-work B' is mounted the hoisting-drums and other machinery for operating the buckets G' and the 120 small cars K'.

M' represents the main driving-shaft mounted on suitable bearings and pillow-blocks M² on a frame-work, M³, upon the floor B⁷. This shaft M' is adapted to be revolved continuously either by an engine upon the floor B⁷ or power applied in any other manner. Upon this shaft M' is mounted a friction-pinion, M⁴, while upon either side of it upon counter- 130

shafts $M^5 M^6$ are two friction-wheels, $M^7 M^8$. Each of these counter-shafts is supplied with a drum, $M^9 M^{10}$, the drum M^9 adapted to receive a cable, v' , one end of which is attached 5 to the car K' , while the other end, after being wound about the drum M^9 a number of turns, runs through the car K' or through the open space between its axles and its hopper-shaped bottom, and thence to the outer ends of the 10 small tracks t' , upon which the car is to run, (the tracks t' being shown in Fig. 7,) thence around a snatch block or sheave, v^2 , on the outer part of the trestle-work, and thence back to and around a brake-rod, K^2 , mounted 15 upon the outer end of the car K' . The extension of the cable v' and the snatch block or sheave v^2 are shown in the drawings in Fig. 7.

By revolving the brake-rod K^2 the cable v' may be wound around it to take up the tension or to tighten the cable, and also to take up any slack caused by the stretching of the cable. By this means the distance which the car travels can be regulated. The cable v' , as before stated, will be wrapped around the 20 drum M^9 a number of turns, so that when the drum is revolved in one direction it will draw the car K' toward it or beneath the hopper B^5 , while if it be revolved in the opposite direction it will draw the car in the opposite 25 direction. Thus the cars K' may be run outward to any desired point, and then back again to their positions beneath the hopper B^5 by merely reversing the motion of the drum M^9 .

30 An automatic trip mechanism will be arranged upon each of the cars K' to release the catches which hold the doors of the car K' , and arranged to be set at any point on the track t' over which the cars run, so that the load may be dumped at any desired point. 35 This automatic tripping mechanism is shown attached to all the cars in all the views, but more clearly in Figs. 9, 10, and 11.

On one end of each of the cars K' is pivoted 40 a small lever, c' , with one end extending out beyond the sides of the car and supported by one end of a smaller lever or latch, c^2 , pivoted at c^3 on the side of the car.

A chain, c^4 , runs from the lever c' around 45 a sheave, c^5 , on the end of the car, and thence inward beneath the car, where it is divided into two parts, $c^6 c^7$, and runs in opposite directions around sheaves $c^8 c^9$, and each part attached to one of the swinging doors $K^3 K^4$ 50 of the car. By this means it will be seen that when the lever c' is held upward by the latch c^2 the doors $K^3 K^4$ will be held closed by the chains $c^4 c^6 c^7$. The latch c^2 is pivoted centrally, as before stated, to the car K' , and is 55 provided on the end opposite to the end which extends beneath the lever c' with a rod, c^{10} , which extends downward and is provided with a head or enlargement, c^{11} , adapted to be held beneath a catch, c^{12} , on the side of the 60 car. This catch is open on its outer side, so that the rod c^{10} may be pulled out of contact with it to release the rod c^{10} and latch c^2 .

By this simple arrangement the head or enlargement c^{11} holds the rod c^{10} and latch c^2 downward, and the latter in turn holds the 70 doors $K^3 K^4$ closed by the chains $c^4 c^6 c^7$, as before described, so that so long as the rod c^{10} is held in the catch c^{12} the doors $K^3 K^4$ will be held closed. The rod c^{10} will extend downward below the enlargement c^{11} , so that it will 75 strike and be thrown out of the catch c^{12} by an inclined trip-plate, c^{13} , adapted to be attached to the frame supporting the rails t' wherever it is desired to dump the loads of the cars. These trip-plates c^{13} will be movable, so that 80 they can be set at any desired point on the frame-work of the rails t' .

On the shaft M^6 is another drum, M^{10} , to which the free end of the hoisting-cable g is attached, so that the revolving of this drum 85 will elevate the bucket G' . The ends of the shafts $M^5 M^6$ next to the driving-wheels $M^1 M^8$ are journaled in eccentric collars $M^{11} M^{12}$, which in turn are journaled in boxes or bearings M^{13} 90 M^4 fast to the frame M^3 , so that the revolving of the eccentric collars will throw the shafts $M^5 M^6$ nearer to or farther away from the friction-pinion M^4 , to throw the friction-wheel $M^7 M^8$ in and out of contact with the constantly-revolving friction pinion. By this means both 95 of the drums $M^9 M^{10}$, or either one of them separately, may be thrown into contact with the friction-pinion to elevate the bucket G' or to move the car K' backward and forward upon its tracks.

Attached to the eccentric collar M^{12} is a lever or arm, N' , to the upper end of which a substantially-horizontal lever, N^2 , is pivoted by one end, while the other end of the horizontal lever is pivoted to one arm of a bell-crank, N^3 . The other arm of this bell-crank is connected with a substantially upright lever, N^4 , having a rack, N^5 , upon its upper end adapted to be moved upward and downward by a pinion, N^6 , journaled on the frame B' . The shaft of this pinion N^6 will be provided with a crank, by which it may be operated. In practice this pinion will be arranged at some distance upon the frame-work B' , convenient to the hand of the operator, who will stand upon a platform 110 about on a level with the top of the hopper. By this means the operator is in a position where he can observe the operation of the buckets, and by the use of the pinion N^6 and rack N^5 115 can have perfect control over the hoisting machinery, as the turning of the pinion will raise and lower the lever N^4 upward and downward, and thus, through the bell-crank N^3 , lever N^2 , and arm N' , attached to the eccentric collar M^{12} , move the friction-wheel M^8 against the 120 friction-pinion M^4 or away from it, and thus 125 operate the bucket or allow it to remain stationary or run backward, as required.

The other eccentric collar, M^{11} , is also provided with an arm, P' , similar to the arm N' , 130 to which levers $P^2 P^3$ are connected, convenient to the hand of the operator, whose duty it is to run the cars K' inward and outward.

Suspended by a yoke-frame, P^4 , beneath the

nearest point of contact of the friction-wheel M^7 and friction-pinion M^4 , is another friction-pinion or idler, P^5 .

The yoke-frame P^4 is connected at its upper end with the short arm of a lever, P^6 , convenient to the hand of the operator. It will thus be seen that if the lever P^3 be drawn upward the large friction-wheel M^7 will be thrown in contact with the friction-pinion M^4 , and thus cause the drum M^9 to wind up the cable v' and draw the car K' inward toward the hopper B^5 , ready to be filled. Then the moment the car is in position beneath the hopper the levers P^2 P^3 will be released and the motions of the car stopped. Then when the car is loaded and ready to be moved out to be dumped the operator pushes down upon the other lever, P^6 , and elevates the idle pinion P^5 , up into contact with both the pinions M^4 and wheel M^7 , and connects the large friction-wheel M^7 with the friction-pinion M^4 through the idler P^5 , thereby reversing the motion of the drum M^9 , and causing it to draw in on that part of the cable v' running from it to the snatch-block v^2 , before mentioned, and thus draw the car outward to the point where it is to be dumped. These levers P^2 P^3 and P^6 may be provided with ropes running over pulleys, &c., so that the pulling of the ropes will operate the levers; but their operation would be the same.

q' is a rope attached by one end to the truck D' , and running upward and backward over a sheave, q^2 , on the frame B' , and thence down to a weight, q^3 . This rope q' will be provided with a movable stop, q^4 , adapted to strike the sheave q^2 when the truck D' pulls the rope q' downward, and limits the movement of the truck upon the inclined section C^2 of the boom. When the truck D' is drawn upward, the weight q^3 runs down and takes up the slack of the rope, and then when the truck runs down again the rope q' will be drawn through the sheave q^2 until the stop q^4 strikes it, which will stop the farther progress of the truck down the boom, and by adjusting the stop q^4 upon the rope the distance which the truck travels down the boom may be regulated to adapt the action of the bucket G' to the location of the hatchway of the vessel, or to the "beam" of the vessel, &c.

Having thus described my invention, what I claim as new, is—

1. In a hoisting apparatus, a frame-work, B' , a boom, composed of a substantially horizontal section, C' , and a downwardly and outwardly inclined section, C^2 , as a continuation thereof, a traveler D' , adapted to run upon said boom as a track, the hoisting bucket suspended from said traveler, and means for elevating said bucket and moving said traveler, substantially as and for the purpose set forth.

2. In a hoisting apparatus, a frame-work, B' , having a receptacle, B^5 , in its lower part, a boom composed of a substantially horizontal section, C' , and a downwardly and outwardly inclined section, C^2 , a traveler, D^2 , adapted to

be moved outward and held toward the front of said horizontal section by a cable and weight or other similar suitable device, a traveler, D' , adapted to run upon said inclined section C^2 , and having the hoisting-bucket G' suspended therefrom, substantially as and for the purpose set forth.

3. The combination of the frame-work B' , having the receptacle or hopper B^5 in its lower part, a boom composed of the substantially horizontal sections C' and the inclined sections C^2 , pivoted supporting-frame C^3 , in which the rear end of said horizontal section is supported, suspension-rods B^3 , outhangers B^2 , guys e , traveler D^2 , provided with the cable and weight, traveler D' , from which the hoisting-bucket G' is suspended, hoisting-cable g , flexible trip $m^3 m^4$, and means whereby said hoisting-bucket is elevated, substantially as set forth.

4. The combination of the frame-work B' , having the receptacle or hopper B^5 in its lower part, a boom composed of substantially horizontal section C' and inclined section C^2 , pivoted supporting-frame C^3 , in which the rear of said horizontal section is supported, outhangers B^2 , guys e , traveler D^2 , provided with cable and weight, traveler D' , from which the hoisting-bucket G' is suspended, hoisting-cable g , flexible trip $m^3 m^4$, main driving-shaft M^1 , carrying the friction-pinion M^4 , counter-shaft M^6 , carrying friction-wheel M^8 , and drum M^{10} , to which the end of said hoisting-cable is attached, and means whereby said friction-wheel may be thrown in contact with and disconnected from said friction-pinion, substantially as and for the purpose set forth.

5. In a hoisting apparatus, a frame-work, B' , a boom composed of a substantially horizontal section, C' , and a downwardly and outwardly inclined section, C^2 , as a continuation thereof, and adapted to be adjusted laterally within said frame-work, a traveler, D' , adapted to run upon said boom as a track, the hoisting-bucket suspended from said traveler, and means for elevating said bucket and moving said traveler, substantially as and for the purpose set forth.

6. In a hoisting apparatus, a supporting-trestle or frame-work, A , having a series of rails, $a' a^2 a^3$, a frame-work, B' , supported upon said rails by trucks b , and provided with receiver B^5 , adjustable boom $C' C^2$, and bucket G , means for elevating said bucket and dumping its contents into said receiver, tracks t in said frame B' , upon which a car, K' , is adapted to run, a system of extended rails, t' , corresponding to said rails t and at right angles to said frame A , and rails $a' a^2 a^3$, a pair of rails, t' , at right angles to said rail t' , and connected therewith by turn-tables T , substantially as and for the purpose set forth.

7. The combination, with a frame, B' , having receiver B^5 and supporting a swinging boom, $C' C^2$, upon which a bucket, G' , is adapted to be elevated to dump its contents into said receiver, and provided with rails t , on

which a car, K', is adapted to run, and adapted to be moved upon rails a' a² a³ of a system of rails, t', corresponding to said rails t, the ends of said rails t' being adjustable at their junction with said rails t, substantially as and for the purpose set forth.

8. The combination of a frame, B', having receptacle B⁵, and rails t, an extended system of rails, t', car K', adapted to run upon said rails, and provided with hinged sides, K³ K⁴, automatic tipping mechanism consisting of the levers c', chains c⁴ c⁶ c⁷, latch c⁸, rod c¹⁰, having enlargement c¹¹, catch c¹², adjustable

trip-block c¹³, drum M⁹, cable v', snatch-block v², tightening-rod K², and means, substantially 15 as described, whereby the motion of said drum may be reversed, as and for the purpose set forth.

In testimony whereof I have hereunto set my hand in the presence of two subscribing 20 witnesses.

ARCHELAUS PUGH.

Witnesses:

JOHN B. SANBORN,
C. N. WOODWARD.
